CONTROLLING ELECTRICALLY-PROPELLED VESSELS.

1,242,357.

Specification of Letters Patent.

Patented Oct. 9, 1917.

Application filed April 16, 1915. Serial No. 21,906.

To all whom it may concern:

Be it known that I, BIRGER LJUNGSTRÖM, a subject of the King of Sweden, citizen of Sweden, residing at Regeringsgatan 52, 5 Stockholm, Sweden, have invented certain new and useful Improvements in Controlling Electrically-Propelled Vessels, of which the following is a specification.

This invention relates to devices for controlling the movement of vessels propelled by electric motors, the generators of which may be actuated by steam-turbines, and it relates especially to such devices when applied and adapted to electric motors and 10 generators using alternating current with variable resistances and divers phases. The said invention consists chiefly in the combination of a controlling rock-shaft with resistance regulating means and means for reversing the current, both being carried thereby and arranged so that the rocking movement of the shaft in either direction from a central position of maximum resistance and minimum speed will progressively 15 reduce resistance until the latter is cut out altogether and the maximum speed forward or backward is attained, the reversing of the current and of the action of the motor being caused by the same rocking movement 20 of the shaft in either direction as it passes the central position. The said invention also consists in the combination with the above devices of supplemental means for short circuiting the entire resistance to insure this action when the shaft is turned to 25 the position of greatest speed in either direction. The said invention further consists in certain details of construction and combination of the various devices employed as 30 hereinafter more particularly set forth and claimed.

In the accompanying drawings:

Figure 1 represents an end elevation of mechanism embodying my invention, one of 45 the slotted guide brackets being shown in vertical section;

Fig. 2 represents a side elevation of the same.

A frame α of any convenient form supports the governing mechanism for speed 50 and direction. In this frame is mounted a shaft b , provided with a hand-wheel a for turning it on its axis in either direction at will and geared by an endless chain or belt t 55 or other convenient means for transmitting

motion to the speed-controlling and direction-controlling crank-shaft c , the double crank d being located at the middle of this shaft and having suspended therefrom a resistance-governing bar e rising and falling 60 with the movement of said crank and shaft in either direction. When said shaft and crank are in the middle position the resistance is at its maximum. The arrangement of the resistance and of the said bar are such 65 that the movement of the bar when the shaft is turned in either direction operates to cut off sections of the resistance or otherwise regularly reduce the same, until in the highest position attainable in such movement the resistance is wholly cut out and ended, so that the maximum of speed of the motor and the vessel will be reached.

The shaft c also carries two eccentrics $f' f^2$ coöperating with studs $h^3 h^4$, carried by two 75 vertically movable bars $h' h^2$, which are respectively attached to the middle parts of levers $i' i^2$, the latter being hung pivotally at one end by links j from the frame α and suspending from their operative ends the 80 rods or bars $n n'$ which operate the motor reversing switches $l' l^2$ by raising and lowering certain parts of the latter. The middle portions of said levers rise and fall with bars $h' h^2$ in guide-brackets s fixed to said 85 frame, the sides of said bracket being slotted to permit such upward and downward movement of said levers.

Each of the eccentrics $f' f^2$ carries a projecting cam arranged to operate the stud h^3 90 h^4 , said parts being arranged to operate the respective switches $l' l^2$ when the crank shaft c turns past its neutral or middle point in one direction or the other. To this end the cams are arranged as shown in Fig. 2 on opposite parts of the eccentrics.

The switches $l' l^2$ are connected with the motors by a parallel series of circuit wires and with the resistances by a corresponding series in practical continuation thereof, 100 these circuit wires, marked o and p , are connected to the respective switches aforesaid, corresponding to the phases of the motor and to the sections of the resistance. In one of said switches the phases are connected 105 in one manner, in the other switch in another manner, to provide for reversing the action of the motor.

In order to insure reliable short circuiting of the entire resistance when the shaft 110

e is at the position of greatest speed forward or backward, additional switches *m m'* are employed, the same being operated by crank *d*, so that if by any chance the resistance 5 has not been wholly cut out by the movement of bar *e* the switch *m* or *m'* will effect this result at the proper time. These additional switches are not indispensable, however, as the bar *e* will always suffice unless 10 in case of some accident or very unusual condition. The contacts of said switches *m* and *m'* correspond in number to the phases of the motor and to the sections of the resistance.

15 As the wheel *a* is turned by hand in either direction away from its middle position the corresponding movement of shaft *c* causes, through its crank *d*, the bar *e* to move so as to progressively cut out one after 20 another of the resistance sections or otherwise steadily lessen the resistance. If continued to its extreme position in this direction it eliminates the resistance altogether and the vessel is at full speed, forward or 25 backward, as the case may be. A movement in the reverse direction of course steadily increases the resistance until the middle point is reached when the switch *l'* or *l''*, which has been controlling the phases is cut 30 out and the other switch *l'* or *l''* switched in, reversing the motor but otherwise operating as before.

This invention does not at all include the construction of the generator A, Fig. 2, the 35 motor B, the resistance C, the switches *l' l''* nor the electric connections *o' o'', p p'*. It is merely required that the same shaft shall be adapted to actuate by the same movement the reversing of the alternating motor or 40 motors and the gradual increase or decrease of resistance and consequently of speed, ending in eliminating the former and reaching the maximum of the latter.

Having thus described my invention, what 45 I claim as new and desire to secure by Letters Patent is:

1. A rock-shaft for controlling both speed and direction, in combination with resistance-governing means actuated by said shaft 50 to progressively reduce resistance and increase speed as said shaft is rocked in either direction from a middle position, a pair of eccentrics carried by said shaft and arranged to operate reversely with respect to each 55 other, a pair of switches for an electro-motor circuit arranged to reverse the direction of motor operation as said shaft turns past said middle point and intervening de-

vices whereby said eccentrics actuate said switches alternately as set forth. 60

2. In combination with a shaft having a crank and means for operating the same, a resistance-governing bar dependent from said crank and lifted thereby as it turns upward from its lowest position in either direction, a pair of eccentrics turning with said shaft, a pair of electric switches, a pair of levers from which the movable parts of said switches are suspended, a pair of bars to which said levers are attached and which 65 are provided with studs engaging said eccentrics, and the necessary conductors of an electro-motor circuit connected to and governed by said switches. 70

3. In combination with a rock-shaft and 75 connections for gradually reducing electrical resistance as said shaft is rocked in either direction from a middle position, a pair of eccentrics carried by said shaft, a pair of bars raised and lowered by said eccentrics, a pair of levers attached to and moving with said bars, slotted guiding brackets for said bars and levers, a pair of switches for reversing an alternating current of several phases and means connecting 80 said levers to parts of said switches for actuating the latter as said bars move up and down, the construction and arrangement of said eccentrics providing for such actuation of the switches as said middle point is 85 approximately passed. 90

4. In combination with means for reducing resistance, means for operating the reversing switches of an alternating current of divers phases, supplemental switches 95 adapted to said phases for cutting out all resistance, and a crank-shaft carrying said means of both kinds and actuating said supplemental switches, the said devices being arranged to decrease resistance and thereby 100 increase speed as the shaft is turned in either direction away from its middle position, to insure the cutting out of all resistance when the extreme position of said shaft in either direction is reached and to reverse 105 the current through the several phases when the crank shaft approaches its middle position.

In testimony whereof, I have signed my name to this specification in the presence of 110 two subscribing witnesses.

BIRGER LJUNGSTRÖM.
